RAILWAY CROSSTIE

Filed March 11, 1930

INVENTOR

BY Homer M. Hadley

Lyon & Lyon ATTORNEYS.

UNITED STATES PATENT OFFICE

HOMER M. HADLEY, OF SEATTLE, WASHINGTON

RAILWAY CROSSTIE

Application filed March 11, 1930. Serial No. 434,863.

This invention relates to constructions in which an upper member must be secured to a base member or support, and the invention is particularly adaptable to situations in which the base member is molded, for example, constructions employing concrete or cement in which an upper member must be secured immovably on the concrete.

While the invention is applicable in various situations, it is particularly useful when embodied in the construction of molded articles such as concrete railway ties or similar articles.

The general object of the invention is to improve constructions of this type and to provide simple means for effecting a connection as suggested above without necessitating the molding of fixed bolts in the molded article, one of my purposes being to overcome the objection to such molded bolts that if they become broken they can not readily be replaced.

One of the objects of my invention is to provide a construction which will enable an attaching bolt to be readily mounted in a molded article such as a cross tie, and also to provide simple means to cooperate with the bolt to enable it to operate effectively as a holding-down bolt.

A further object of the invention is to produce a molded cross tie having a construction which operates to reduce the amount of material used in the cross tie and at the same time increases the efficiency of the cross tie when laid in a railway road-bed.

35 A further object of the invention is to provide a construction for holding down an upper member, such as a railroad rail, on a base by means so related that any tendency of the held-down member or rail to move, increases the clamping effect of holding-down means.

Further objects of the invention will appear hereinafter.

The invention consists in the novel parts and combinations of parts to be described hereinafter, all of which contribute to produce an efficient railway cross tie.

A preferred embodiment of the invention is described in the following specification, while the broad scope of the invention is pointed out in the appended claims.

In the drawings:

Figure 1 is a plan of a portion of a railway tie embodying my invention, one end of the tie being broken away; this view also shows a short portion of a railroad rail lying on the cross tie and broken away, the web of the rail being shown in horizontal section.

Figure 2 is a side elevation of the cross tie illustrated in Figure 1 and illustrating my holding-down means and its relation to the rail, a portion of which is shown in cross-section together with some of the parts. A portion of the cross tie is shown broken away and at one side of the rail the holding-down means is illustrated in side elevation.

Figure 3 is a vertical cross-section through the cross tie taken on the line 3—3 of Figure 1.

Figure 4 is a perspective of a bolt which is a feature of my invention and which is used with a base member such as a cross tie embodying my invention.

Before proceeding to a detailed description of the invention as applied to a cross tie, it should be stated that where bolts are employed embedded in concrete or the like for holding down upper members or structures, and where the situation is such that the projecting ends of the bolts may become injured in shipment or in use, great inconvenience is encountered in removing the bolt from the concrete. For example, concrete cross ties have been employed in which bolts were molded permanently in the concrete with projecting studs, but it is difficult to have these studs aligned with sufficient accuracy to enable them to operate effectively for holding the rail base in position. It is desirable in such a construction to have some means in connection with the fastening means for enabling it to be adapted to special situations; for example, on curves where the rails are not straight and the edge of the rail flange may not be located exactly in its ideal position to cooperate with a fixed fastening bolt. My invention is intended to overcome these difficulties and to provide a simple construction whereby a bolt can be readily applied in the concrete base member such as a cross tie after the base member or tie has been molded.

The invention involves the use of a socket extending into the molded piece from its upper face and this socket is formed so that its axis is disposed on a helix. The helix is preferably of relatively high pitch and may be either left-hand or right-hand in character.

As applied to a railway cross tie, one of my purposes has been to provide a construction such that tendencies of the rail to move on the tie will have the effect of tightening up the grip of the fastening device on the rail flange.

I shall now proceed to describe the invention as applied to a cross tie and the means embodied with the cross tie to secure the rail flange to it.

Referring more particularly to Figures 1 and 2, 1 represents a railway cross tie which is molded of suitable material such as cement or concrete. According to my invention I form the body of this tie of substantially rectangular cross-section at its ends, as at 2, the railway tie being formed at two points on its length into rail seats 3 at which the same substantially rectangular cross-section is employed. At intermediate points between the rail seats the cross tie is formed with heads, such as the head 4, which are also of rectangular cross-section the same as the ends and at the seats 3 of the tie.

In order to economize the molding material and also to give the tie improved qualities when in use in a road-bed, I provide the tie on opposite sides with a plurality of 35 pockets 5. These pockets are relatively deep and extend into the side of the tie nearly to the axis of the tie so that at the points where these pockets are located the tie has the typical I-shaped cross-section illustrated in Figure 3. Any suitable reinforcing means 6 may be employed in constructing the tie; in the present instance the reinforcing includes narrow loops 7 of wire connecting elongated relatively heavy longitudinal bars 8 that are located in the heads of the I (see Fig. 3).

At points where the tie has a rectangular cross-section, I employ rectangular loops 9 of wire which extend around on the interior of the tie as illustrated in Figure 3, and pass around longitudinal corner rods 10 of larger diameter.

At each rail seat 3, and on opposite sides of the location of the rail 11, I provide the body of the tie with two bolt sockets 12. 55 These sockets are formed so that the axis of the socket is disposed along a helix and preferably the socket extends all the way through to the bottom of the tie so as to form a bottom opening 13 on the under side of the tie.

This socket 12 emerges on the upper face of the tie to form an elongated or elliptical opening 14, the longitudinal axis of which is disposed at right angles to the longitudinal axis of the rail. This opening 14 is located

so that with reference to the axis 15 of the helix it is disposed toward the center of the tie. In order to give the greatest possible strength in the construction, it is preferably located toward the center line of the tie, the socket being located to one side of the longitudinal axis of the tie (see Fig. 1). Furthermore, there is preferably a certain relation between the character of the helix and the location of the opening 14, as will appear more clearly hereinafter. As illustrated in Figure 1, for example, the helix is left-hand in character, so that if an object were passed into the opening 14, it would move in an anti-clock-wise direction in passing down into the helix.

In Figure 4 I illustrate a bolt 16 that I employ with this socket. This bolt has a body which is disposed in a helix of the same pitch and character as the socket 12, the upper end of the bolt terminating in a substantially straight stud 17, which is intended to cooperate with holding-down means to engage the article, such as a rail flange, that is to be secured to the base member or cross tie. This stud 17 is preferably provided with ordinary screw threads to receive a nut 18.

When molding the cross tie a helical molding form having the shape illustrated in Figure 4 is embedded in the molded body and just as the material commences to set this forming member is removed by drawing it outwardly and at the same time rotating it on the axis of the helix. In this way these helical sockets 12 can be readily molded in the concrete tie.

Any suitable means may be provided to cooperate with the projecting stud 17 to enable it to hold down an upper member on the base member or cross tie.

In the present instance, in order to hold down the flange 19 of the rail, I provide a washer or lug 20 to cooperate with each projecting stud. Each washer has a nose 21 to project over the edge of the rail flange and formed to fit to the same, and furthermore, each lug is preferably formed with an elongated opening such as a slot 22 that fits to the side of the stud 17. In order to back up the lug and hold it against the edge of the flange, I prefer to employ one or more shims of crescent shape, such as illustrated at the shim 23 in Figure 1. A similar shim 24 is illustrated in Figure 2 and shown in cross-section. If the openings, such as the opening 14, are located near the longitudinal axis of the tie, I prefer to use a helix of left-hand character.

In fastening the rail down onto the tie, it is put in place in a mid position on the rail seat 3 and the bolts 16 are screwed down into their sockets 12, and the lugs and nuts 18 applied as indicated. Referring to Figure 1, it will be evident that when the parts are in place, if there is any tendency of the

5 rail to shift toward the left, thereby exerting pressure on the lug 20 (see Fig. 2) tending to displace the lug toward the left, this will cause the shim 24 to press against the
 10 inner side face of the stud 17. This tends to rotate the bolt in a direction to carry it further down into the helical socket and this will increase the pressure of the nut 18 on the upper face of the lug. Furthermore, if
 15 there is any tendency of the rail flange to lift, this will produce an upward pressure on the side of the nut 18, and this tends to pull the bolt out of its socket. Pulling the bolt out of the socket, however, tends to produce a movement of the stud 17 toward the rail, and this increases the gripping power of the nose of the dog on the edge of the rail flange.

20 When the tie is in use in the road-bed of the track, the ballast 25 extends into the pockets 5, and this gives a considerable weight of ballast exerting its weight on the bottom faces 26 of the pockets, thereby holding the tie more securely in the road-bed.

25 Furthermore, if there is any tendency of the tie to rock laterally on its longitudinal axis, this rocking movement is considerably resisted by the faces 26 and also by the upper faces 27 that form the upper walls of the pockets. This form of cross-section for the tie therefore holds the tie very rigidly in the road-bed and effectively resists any "pumping" action of the tie which might occur by the passing over of heavy rolling stock.

30 It will be evident that when there is an upward pull on the studs 17, there might be a tendency for the concrete to chip off or break near the point where the helix emerges from the helical socket. For this reason it is
 35 preferable to provide reinforcements such as indicated by the reinforcing wires 28. These wires are in the form of long links, the upper end of each link forming a loop 29 around the helical socket near its upper end.
 40 These reinforcing links extend in a diagonal direction, crossing each other under the middle of the rail seat 3, as indicated in Figures 1 and 2.

45 It is understood that the embodiment of the invention described herein is only one of the many embodiments this invention may take, and I do not wish to be limited in the practice of the invention, nor in the claims, to the particular embodiment set forth.

50 What I claim is:

1. A railway cross-tie consisting of an elongated molded body having a plurality of pockets formed in the side faces thereof to receive ballast when the tie is laid in the road-bed, said cross-tie having a plurality of sockets formed in the upper face thereof and extending down into the interior of the tie, the axes of said sockets being disposed in a helix, and bolts having helical bodies screwed into the said sockets, said bolts each having a stud

at its upper end projecting substantially vertically to cooperate with means for engaging the rail flange.

2. A railway cross-tie consisting of an elongated molded body having a plurality of pockets formed in the side faces thereof to receive ballast when the tie is laid in the road-bed, said cross-tie having a plurality of sockets formed in the upper face thereof and extending down into the interior of the tie, the axes of said sockets being disposed in a helix, rail-holding bolts having helical bodies screwed into the said sockets, said bolts each having a stud at its upper end projecting substantially vertically to cooperate with means for engaging the rail flange, each of said sockets emerging at an opening on the upper face of the tie located so that when the bolt is being seated the stud of the bolt is located with reference to the axis of the helix so that the rotation of the bolt into the socket will move the stud away from the location of the rail flange.

3. A railway cross-tie consisting of an elongated concrete body with a rail seat formed thereon toward each end of the tie, said body at said rail seat having a bolt-socket extending down with its axis disposed in a helix and emerging on the upper face of the tie at said seat to form an opening in the upper face of the tie located toward the side of the tie with reference to the axis of the helix, and a bolt received in the socket having a helical body adapted to be screwed into the helix through the said opening, said bolt having a threaded stud at its upper end, a nut received on said stud, and clamping means on the stud under the nut for engaging the flange of the rail.

4. A railway cross-tie consisting of an elongated concrete body with a rail seat formed thereon toward each end of the tie, said body at said rail seat having a bolt-socket extending down with its axis disposed in a helix and emerging on the upper face of the tie at said seat to form an opening in the upper face of the tie located toward the side of the tie with reference to the axis of the helix, and a bolt received in the socket having a helical body adapted to be screwed into the helix through the said opening, said bolt having a threaded stud at its upper end, a nut received on said stud, and clamping means on the stud under the nut for engaging the flange of the rail, said opening and said helix being so related that when the bolt is substantially seated the stud will be moving around the axis of the helix away from the middle portion of the rail seat.

5. A railway cross-tie consisting of an elongated concrete body with a rail seat formed thereon toward each end of the tie, said body at said rail seat having a bolt socket extending down into the same, the axis of said socket being disposed in a helix and

- emerging on the upper face of the tie to form an opening located toward the side of the tie with reference to the axis of the helix, and a bolt having a helical body received in the said socket through the said opening, said bolt having a threaded stud at its upper end, a nut received on said stud, and a holding-down lug received on the stud under the nut having a nose to project over the flange of the rail.
6. A railway cross-tie consisting of an elongated concrete body with a rail seat formed thereon toward each end of the tie, said body at said rail seat having a bolt socket extending down into the same, the axis 15 of said socket being disposed in a helix and emerging on the upper face of the tie to form an opening located toward the side of the tie with reference to the axis of the helix, and a bolt having a helical body received in the said socket through the said opening, said bolt having a threaded stud at its upper end, a nut received on said stud, and a holding-down lug received on the stud under the nut having a nose to project over the flange of the rail, said lug having an elongated opening therein to receive the stud and a shim located in the opening between the stud and the end of the said opening to back-up the lug against the edge of the rail flange.
7. A railway cross-tie consisting of an elongated molded body with a rail seat formed thereon toward each end of the tie, said body at said rail seat having a bolt socket extending down into the same, said 35 socket having its axis disposed in a helix and emerging on the upper face of the tie at said seat.
8. A railway cross-tie consisting of an elongated molded body with a rail seat formed thereon toward each end of the tie, said body at said rail seat having a bolt socket extending down into the same, said socket having its axis disposed in a helix and emerging on the upper face of the tie at said seat, and a bolt having a helical body received in the said socket and having a threaded stud at its upper end projecting up from the upper face of the tie.
9. A molded member having a socket extending into the same through its face, said 50 socket having its axis disposed in a helix, and a bolt having a helical body received in the said socket and having a substantially straight extension at its outer end projecting from the said face to cooperate with holding-down means.
10. A railway cross-tie consisting of an elongated molded body having a plurality of 60 pockets formed in the side faces thereof to receive ballast when the tie is laid in the road-bed, said cross-tie having a plurality of sockets formed in the upper face thereof and extending down into the interior of the tie, the axes of said sockets being disposed in a high pitch helix.
11. A railway cross-tie consisting of an elongated body with rail seats, formed of reinforced concrete having a substantial rectangular cross-section at its ends, at the rail seats and at a plurality of points located between the rail seats, and having a plurality of pockets formed on the side faces thereof to receive ballast when the tie is laid in the road-bed.
12. A railway cross-tie consisting of an 75 elongated molded body with a rail seat formed thereon toward each end of the tie, said body at said rail seat having a bolt socket extending down into the same, said socket having its axis disposed in a helix and emerging on the upper face of the tie at said seat, and reinforcing means embedded in the cross-tie and reinforcing the said socket near its point of emergence on the upper face of the cross-tie.
13. A railway cross-tie consisting of an 80 elongated molded body with a rail seat formed thereon toward each end of the tie, said body at said rail seat having a bolt socket extending down into the same, said socket having its axis disposed in a helix and emerging on the upper face of the tie at said seat, a bolt having a threaded stud at its upper end projecting up from the upper face of the tie, and reinforcing means in the form of a link 85 embedded in the cross-tie and having a loop extending over the upper portion of the helical body of the bolt adjacent the stud.
14. A railway cross-tie consisting of an 90 elongated molded body having a plurality of 100 pockets formed in the side faces thereof, said pockets operating to receive ballast when the tie is laid in the road-bed, the faces of said pockets cooperating with the ballast to hold the tie in the position in which it is laid in the 105 road-bed, said cross-tie having a pair of sockets separated from each other on a line inclined to the axis of the tie and located respectively adjacent each end of the tie, to receive fasteners located respectively on opposite sides of the rail when laid on the tie.
- Signed at Los Angeles, California, this 21st day of February, 1930.
